UNITED STATES PATENT OFFICE.

LOUIS BREGUET, OF VELIZY-VILLACOUBLAY, FRANCE, ASSIGNOR TO SOCIÉTÉ ANONYME DES ATELIERS D'AVIATION LOUIS BREGUET, OF PARIS, FRANCE.

AIRCRAFT.

Application filed January 25, 1921. Serial No. 439,848.

To all whom it may concern:

Be it known that I, LOUIS BREGUET, a citizen of the Republic of France, residing in Velizy-Villacoublay (Seine-et-Oise), France, have invented new and useful Improvements in Aircraft, which is fully set forth in the following specification.

This invention has for its principal object to provide aircraft with stream-line tubular struts presenting lessened and equal resistance to bending in every direction.

In the construction of aircraft, round tubes are generally employed to intertie upper and lower longitudinals.

According to the present invention the resistance to the wind which is presented by a circular cross-section is considerably reduced by the employment of tubes of stream-line section. As a set-off to such a section, the moments of inertia in relation to the two principal axes are unequal. In determining the resistance to bending the minimum moment of inertia must be taken into account. Therefore the stream-line tubes, for a given end thrust load, have a section and weight greater than would be the case with an ordinary tube giving the same resistance to bending in every direction.

It is for the purpose of ensuring equal resistance to bending that the struts according to the present invention have been constructed, the said struts being each composed of, or comprising, two curved tubes of stream-line form in transverse section, their ends being fitted and secured in U-shaped connecting, or elbow, pieces and they being reinforced by cross-braces.

The following description, with reference to the accompanying drawing, gives an example which will enable the manner in which the invention can be carried out to be fully understood.

Figure 1 is a transverse section of a stream-line tube.

Figure 2 is an elevation of a strut made in accordance with one way, and Figure 3 is an elevation of a strut made in accordance with another way, of carrying out this invention.

Figure 4 is an elevation, in a plane, at right angles to that of Figures 2 and 3.

Figure 5 is a detail (drawn to a larger scale) showing an arrangement for connecting the struts with the longitudinals.

The two principal moments of inertia of a

tube of a section such as that shown in Figure 1, are taken in relation to the two axes O,X, and O,Y, and, in determining the resistance to bending, the minimum moment of inertia in relation to O,Y, must be taken into account.

In order to obtain equal resistance to bending in every direction, each strut is made with two curved tubes V and V¹ of stream-line form in transverse section, the ends of the said tubes being mounted in U-shaped connecting-, or elbow-, pieces N. Tubes forming cross-stays, are fixed by soldering, brazing, or riveting, at AB, CD, EF, to limit the unsupported lengths subjected to bending in the direction of the arrows J.

The distance between CD is chosen so as to ensure the same resistance to bending in the two directions O,X, and O,Y.

The system of connecting the struts with the longitudinals may be of the ball-and-socket type, and may consist, for example, of a partially spherical piece R (Figure 5) in one with the lower and upper elbow-pieces N, and arranged in a socket-piece S, riveted to the corresponding longitudinal and secured in position by a screw-cap S¹.

In order to lessen the strain tending to bring the cross-stays A,B; C,D; and E,F, out of the straight in relation to the stream-line tubes, the places at which the said cross-stays are attached to the stream-line tubes V,V¹, are furnished with cross-braces A,D; B,C; C,F; and D,E, as indicated in Figure 3.

In order to ensure good resistance in the perpendicular plane, other diagonal cross-braces K can be employed to connect the front strut V with the rear-strut V⁰, as indicated in Figure 4, one brace connecting the upper end of the front strut to the lower end of the rear-strut and vice versa with the other brace.

These braces K, are connected together by a mid-plate P. Two tubes, T and T⁰, connect the plate P with the middle of the struts.

The result of this arrangement is that the free lengths exposed to bending stresses in the direction of the arrow L, are reduced about one half, by the tubes T and T⁰, which, with the absorption of but little force, keep the middles of the struts V and V⁰ supported, and transmit the strain to the transverse pieces thus constituting a practically rigid whole.

The described construction furnishes stream-line struts of equal resistance to bending in every direction, the unsupported length being about half that which is the case in ordinary struts.

The tubes T , T' , being of small section, the weight of the whole strut is considerably reduced which is the intention and effect of the diagonal bracing.

10 It is of course understood that the details of the arrangements hereinbefore described are only examples and that the invention is not limited to the precise details hereinbefore described and illustrated, as they 15 may be varied without departing from the nature of this invention.

Having now particularly described and ascertained the nature of this invention, and in what manner the same is to be performed, I declare that what I claim is:

1. An aircraft strut comprising two tubes of curved shape having their concave portions oppositely situated, means for connecting together the ends of the said tubes, 25 means for cross-connecting the two tubes, and means for securing the said strut to the longitudinals.

2. An aircraft strut comprising two tubes of curved shape having their concave portions oppositely situated and of stream line 30 cross-section, double-branched tube-shaped connecting members for attaching the ends of the tubes together, means for cross-con-

necting the two tubes, and means for securing the said strut to the longitudinals.

3. An aircraft strut comprising two tubes of curved shape having their concave portions oppositely situated and of stream line cross-section, double-branched tube-shaped connecting members for attaching the ends of the said tubes together, cross-pieces whose ends are secured to the two tubes for cross-connecting the said strut, together with bracing wires for connecting the said cross-pieces, and a ball-and-socket 45 joint for connecting the said strut to each of the longitudinals.

4. The combination in an aircraft, of a front strut and a rear strut each comprising two tubes of curved shape having their concave portions oppositely situated, and of stream line cross-section, double-branched tube-shaped connecting members for attaching the ends of said tubes together, cross-pieces whose ends are secured to the two 55 tubes for cross-connecting the strut, together with bracing wires for connecting the said cross-pieces, ball-and-socket joints for connecting said struts to the longitudinals of the air-craft, and a cross-bar connecting the 60 forward strut with the corresponding rear strut.

In testimony whereof I have signed this specification.

LOUIS BREGUET.
